UNITED STATES PATENT OFFICE.

BENJAMIN W. GILCHRIST AND GEORGE L. RICE, OF WOODHAVEN, NEW YORK.

ANODE ELEMENT.

No. 922,470.

Specification of Letters Patent.

Patented May 25, 1909.

Application filed June 9, 1908. Serial No. 437,501.

To all whom it may concern:

Be it known that we, BENJAMIN W. GILCHRIST and GEORGE L. RICE, citizens of the United States, and residing at Woodhaven, 5 Long Island, in the county of Queens and State of New York, have invented certain new and useful Improvements in Anode Elements, of which the following is a specification, such as will enable those skilled in the art to which it appertains to make and use the same.

This invention relates to electro-plating and electrotyping apparatus, and the object thereof to provide an improvement in this 15 class of apparatus whereby the life of the material which constitutes the anode proper will be prolonged and whereby a great saving of material may be effected by the use of what is usually regarded as waste or inferior 20 material such as pieces of anodes, scraps, wires or pieces of grain or cube metal, and with this and other objects in view the invention consists in an anode element for apparatus of the class specified constructed as 25 hereinafter described and claimed:

The invention is fully disclosed in the following specification, of which the accompanying drawing forms a part, in which the separate parts of our improvement are designated by suitable reference characters in 30 each of the views, and in which:—

Figure 1 is a longitudinal sectional view of an electrotyping or plating apparatus provided with our improvement; Fig. 2 a transverse section on the line 2—2 of Fig. 1; Fig. 3 a partial section on the line 3—3 of Fig. 1; Fig. 4 a view similar to Fig. 3 but showing only a detail on an enlarged scale; Fig. 5 a sectional detail view of our improved anode 40 element; and, Fig. 6 a horizontal section on the line 6—6 of our improved anode element as shown in Fig. 3 and showing a modification.

In the drawing forming part of this specification, I have shown at *a* the usual solution tank which is oblong and rectangular in form, and across and longitudinally of the top of which are placed two cathode rods or bars *b* and two anode rods or bars *c*, and at *d* we 45 have shown a battery connected with the cathode rods or bars *b* by wires *e* and *e*² and with the anode rods or bars *c* by wires *f* and *f*², the wires *e* and *e*² being the negative wires and the wires *f* and *f*² the positive 50 wires.

Suspended from the cathode rods or bars *b*

are the usual cathode supporters *g* and connected with the rods or bars *c* are the usual anode supporters *h*.

It will be understood that the cathodes proper consist of the work to be treated and in the accompanying drawing, the said work is shown in the form of tubes *g*² supported by the cathode supporters *g*, all this construction being of the usual form.

Our improved anode element which forms the subject matter of this application comprises a box *i* composed of a back *i*², a bottom *i*³, and openwork front *i*⁴, a transverse top *i*⁵ and sides *i*⁶, and between the top *i*⁵ and the openwork front *i*⁴ is an opening *i*⁷. The anode proper is shown at *j* and consists of a plate of the usual form provided at its upper end with ears *j*² which pass upwardly through apertures *j*³ in the top *i*⁵ of the box *i* and with which the supporters *h* are connected as clearly shown in Figs. 1, 2 and 3. The supporters *h* are connected with the ears *j*² of the anode *j* by means of hooks *h*² at the lower ends thereof, and this connection is covered or protected by a rubber sleeve *k* designed to prevent the solution in the tank *a* from coming in contact with the hooks *h*². The supporters *h* being preferably composed of copper, the solution would 85 quickly destroy the hooks *h*² but by covering these hooks with rubber, this result is obviated.

The anode proper designated by the reference character *j*, extends downwardly a predetermined distance into the box *i* preferably about two-thirds of the depth thereof and, in practice, we put into said box scraps or waste material *m*, it being understood that these scraps or waste material are of the same 95 quality as the anode proper. In other words, if the anode *j* consists of gold, the scraps or waste material *m* would be gold also, and if the anode *j* consists of silver then the scraps or waste material *m* would also be of silver. In this way, old or partially consumed anodes 100 may be employed or scraps of any form may be used and this, as will be understood, largely increases the plating surface of the anode, the surfaces of all the separate parts or pieces of scrap being included as a part of the anode proper.

The front *i*⁴ of the box as shown in Fig. 3 is composed of openwork or mesh work of fibrous material, while the back, top, sides 105 and bottom thereof may be composed of rubber, celluloid, asphaltum or fiber, and

when wood is employed the said parts are coated or covered with rubber paint as shown at *n* in Fig. 4, and the openwork fibrous front is also similarly treated.

5. The top *i*⁶ of the box *i* is provided with depending side members *i*⁸ by which it is secured to the side and the back members of said box, in the form of construction shown, but this connection may be made in any 10 desired manner.

In the construction shown in Fig. 6, the front of the box consists of an openwork grate or lattice work *i*⁹ composed of hard rubber or any other suitable material, and 15 this grate may be slid into position or removed from the box whenever necessary for cleaning or other purposes.

The opening *i*⁷ between the top portion of the openwork front of the box and the top of 20 said box is intended to facilitate the insertion of the scrap or waste material *m* into said box and the removal from the box of said material. It will also be observed that the top of the box is narrower than the bottom 25 thereof, and the side walls *i*⁶ of the box between the openwork front and the top thereof are inclined backwardly, and by reason of this construction the top of the box occupies less space in the tank, and this permits of the 30 insertion of large work, or basket work to be plated into the tank, and the much more convenient placing thereof in said tank.

It will be understood, of course, that the anode *j* must always be in connection with 35 the scrap material *m* or with parts thereof, and said scrap material, or the separate parts, thereof must always be in connection. It will also be understood, of course, that the solution *o* in the tank *a* is free to circulate, 40 through the box *i* and the use of this apparatus with our improved anode element will be the same as the use of all other apparatus of this class.

Having fully described our invention, 45 what we claim as new and desire to secure by Letters Patent, is:

1. In an electro-plating apparatus an anode element comprising a box through which the solution is free to circulate, said

box being provided with a top, and an anode 50 adapted to be placed in said box and provided with ears which are passed upwardly therethrough and with which the suspending devices are connected, the connection between the ears of the anode and said suspending 55 devices being covered with rubber or similar material.

2. In an electro-plating apparatus, an anode element comprising a box one side of which is composed of openwork which does 60 not extend to the top of the box whereby an opening is formed in said side at the top of the box, and an anode adapted to be placed in said box and provided with ears which are passed upwardly therethrough and with 65 which the suspending devices are connected.

3. In an electro-plating apparatus, an anode element comprising a box one side of which is composed of openwork which does not extend to the top of the box whereby an 70 opening is formed in said side at the top of the box, and an anode adapted to be placed in said box and provided with ears which are passed upwardly therethrough and with 75 which the suspending devices are connected, the said openwork side being also removable.

4. In an electro-plating apparatus, an anode element comprising a box one side of which is composed of openwork which does not extend to the top of the box whereby an 80 opening is formed in said side at the top of the box, and an anode adapted to be placed in said box and provided with ears which are passed upwardly therethrough and with 85 which the suspending devices are connected, the said openwork side being also removable, and the sides of the box between the said openwork and the top thereof being inclined backwardly.

In testimony that we claim the foregoing 90 as our invention we have signed our names in the presence of the subscribing witnesses this 8th day of June, 1908.

BENJAMIN W. GILCHRIST.
GEORGE L. RICE.
